FLUID AND MATERIAL SAVING DEVICE FOR OIL OR OTHER WELLS

Filed Nov. 9, 1931

Inventor.

A PARYZEK

By Fred D. Haynes

Attorney

UNITED STATES PATENT OFFICE

ADOLPH PARYZEK, OF SANTA BARBARA, CALIFORNIA

FLUID AND MATERIAL SAVING DEVICE FOR OIL OR OTHER WELLS

Application filed November 9, 1931. Serial No. 573,913.

My invention relates to devices adapted for special use in connection with the pipes, casings or tubing of wells, whereby oil, a circulating medium, such as rotary mud and the like, water or gas contained in said pipes, casings, tubing or the like may be saved and not spilled upon the derrick floor, as is now the case in general practice, said devices involving not only a marked saving of the fluid 10 in said pipes, tubing or the like, but also eliminating the deleterious effects of spilling their contents not only on the derrick floors, but also upon the person and clothing of the operators.

It accordingly is an object of my invention to provide a novel form of device comprising a casing, preferably of plural part form, having means for rendering said casing fluid tight, when associated with the pipes, tubing, 20 and the like of wells, said casing being adapted to receive the contents of said pipes or tubing, means being also provided to lock the parts of said casing together when in use, plural means being also provided for suspending said casing in a plurality of ways, or supporting said casing manually, any conventional or novel form of drain means being provided for discharging the contents of said pipes or tubing to distant points, means being 25 also provided for cleaning the device after use, and also for guiding the pipes, tubing or the like into said means for rendering said casing fluid tight.

The above and further objects and advantages of my invention, as will hereinafter more fully appear, I attain by the construction described in the specification and illustrated on the drawing forming a part of my application.

Reference is had to the accompanying drawing, in which similar reference characters denote similar parts. In the drawing,

Fig. 1 is a perspective view illustrating one way in which my invention may be applied to a well tubing, piping or the like,

Fig. 2 is an enlarged side elevational view of my invention, free from the tubing, piping or the like,

Fig. 3 is an end elevational view, looking 50 from the left, Fig. 2,

Fig. 4 is a cross-sectional view, taken on the line 4—4, Fig. 3, looking in the direction of the arrows,

Fig. 5 is an enlarged cross-sectional view, 55 taken on the line 5—5, Fig. 2,

Fig. 6 is an enlarged fragmentary cross-sectional view, taken on the line 6—6, Fig. 2,

Fig. 7 is a fragmentary front elevational view, illustrating how my invention may be supported in a different way than depicted 60 in Fig. 1, and

Fig. 8 is a top plan view, illustrating more particularly the means for guiding the tubing and the like into the packing means of 65 the casing.

Describing my invention more in detail, in its broader aspects said invention comprises a plural part casing, at least two parts of which may be hinged together, said parts having suitable packing glands, preferably 70 positioned at each end of said casing, said glands being adapted to engage the tubing, pipes and the like of oil or other wells, said casing having means whereby it may be suspended or manually held in a plurality of 75 ways, said casing being adapted to receive the fluids or material in said tubing, pipes or the like, so said fluids or material will be saved and not spilled upon the derrick floor 80 or on the clothing or person of the operators, means being also provided for locking said casing in position on said tubing, pipes or the like, and, if desired, a suitable drain means may be associated with said casing, as 85 well as a means for cleaning the same after use.

More specifically, my invention comprises a suitable casing 2, constructed of any preferred material, and of any desired number 90 of parts, in the present instance said casing comprising two complementary arcuate portions 4, hinged together in any suitable way as indicated by the reference numeral 6, which hinge may be of conventional or novel form, 95 said hinge in the present instance comprising an elongated plate 8, to which the parts 4 are hinged as desired, such as a rod and loop construction 10, any preferred packing means 100 12 (Fig. 5) being provided to pack said

hinged portion at the juncture of the portions 4.

The casing 2 is adapted to be locked about the tubing 14, the joint 16, which is to be positioned within said tubing and unscrewed therein, so its contents may be emptied into said casing 2 and not spilled upon the floor of the derrick or upon the person and clothing of the operator.

- 10 To receive and pack the ends of the casing 2 about the tubing 14, the packing glands 18 are provided, which glands may be constructed of any preferred material and may be associated with the casing 2 in any manner 15 in practice preferred, said glands being provided with cut-out portions 20 (Fig. 4, more particularly) in which are positioned in any suitable way the packing material 22 of any desired kind, said glands being preferably of 20 a two part arcuate construction, the parts being movable with the parts 4 of the casing 2, so said parts may be swung toward and away from the tubing 14.

To provide an easy method of guiding the 25 tubing 14 into the cut-out portions 20, the means 24 are provided, which means may be associated with either one or both of the packing glands 18, as in practice preferred, said means preferably comprising a pair of 30 members, such as plates, of suitable configuration and material, affixed to the arcuate portions 4, and in front of the hinge 6, and superimposed upon one another, so that as said portions 4 of the casing 2 are swung together, 35 the protruding ends of said plates will engage the tubing 14 to prevent the same from entering between the adjacent edges of the hinged sections, and thus guiding the same into the cut-out portions 20 of the glands 18, 40 to insure speed of operation, and that the packing material 22 will accurately engage said tubing and hold said tubing firmly in position in the casing 2, without leakage. See Fig. 8.

- 45 To hold the casing 2 securely in the tubing 14, a novel form of locking means, designated generally by the reference numeral 26, may be provided, said locking means preferably comprising a locking bar 28, of single or 50 plural construction, adapted to engage suitable holding devices, such as the hooks 30 of any preferred number, an operating member 32, suitably connected to the bar 28, so said bar may be caused to engage at least one 55 of the hooks 30, said bar, if desired, being also provided with a hook engaging part, such as the bent over portion 34, the other end of said bar, if desired, being off-set, as at 36, to engage the other hook or loop 30. 60 See Fig. 2, more particularly, and said bar 28, if desired, being movable within keepers 38, of any preferred number, and associated as preferred with one of the portions 4. See Fig. 1, more particularly.
- 65 To secure the operating member 32 in posi-

tion, after the parts of the casing 2 are locked, a suitable loop and ratchet mechanism 40 may be provided, comprising a loop 42 and a suitable ratchet 44. See Figs. 1 and 4, more particularly.

Any preferred means for suspending or holding the casing 2 may be provided, and plural means to this end are provided. To suspend the tubing vertically, the bail and loop construction 46 (Figs. 1, 2 and 4) may be provided. To suspend the device horizontally, the loop 48 (Figs. 1 and 2) may be provided, which loop may take any form in practice desired and may be associated with the casing 2 in any way in practice preferred. To hold the casing 2 manually, the foot 50, may be provided, which foot may be associated with said casing in any manner in practice preferred, as by the member 6. Figs. 1, 2, 4 and 7. Where the parts 4 of the casing 2 join, any suitable packing means 52, may be provided. See Fig. 2. Since such a packing means may be of any form in practice preferred, further illustration and description are not deemed needed.

To drain the casing 2, after the joint 16 of the tubing 14 has been disconnected, and the contents thereof emptied into said casing, any preferred drain means, such as the pipe 54, leading to my receptacle, nearby or and distant points, may be provided, and any suitable control valve 56 may be connected to said pipe to control the flow of the contents of said tubing.

If desired, also, any preferred cleaning means 58 may be provided, such means comprising a suitable spray means 60 (Fig. 4, more particularly), connected to a source of fluid supply, such as water, by a pipe 62, which pipe may have a control valve 64 (Fig. 2) for controlling the flow of said fluid, so said fluid may be sprayed within the casing 2 to clean the same, especially where a circulating medium, such as rotary mud, is to be saved and prevented from spilling. My invention may be used to save oil, gas, water, or a circulating medium.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

I claim as my invention:

1. In a device of the class described, including a sectional casing, means for hinging the sections of said casing together, plural means for packing the sections of said casing for rendering said casing fluid tight, a circular spray means in one end of said casing, and a valve controlled pipe connection for

feeding fluid to said spray means, whereby said casing may be cleaned.

2. In a device of the class described adapted for use in connection with a well tubing, 5 a sectional casing, means associated with the sections of said casing for hinging said sections together, arcuate closures associated with said sections for closing said casing as it embraces said tubing, and arcuate overlapping guides associated with one end of said casing for guiding said tubing into said arcuate closures, to prevent said tubing from entering the adjacent edges of said sections.

3. In a device of the class described adapted for use in connection with a pipe, a sectional casing, means for hinging the sections of said casing together, an arcuate sectional closure positioned in each end of said casing, and a set of superimposed arcuate plates, positioned in one end of said casing, for preventing said pipe from entering the adjacent edges of said sections as said device is being positioned on said pipe.

In testimony whereof I have signed my 25 name to this specification.

ADOLPH PARYZEK.
